CAR UNCOUPLER FOR TOY TRAINS

Harold J. Joseph, 1018 N. 5th Ave., Wausau, Wis.

Filed Oct. 13, 1959, Ser. No. 846,128

8 Claims. (Cl. 213—211)

My invention relates to improvements in car uncouplers for toy trains.

Although the car-carried coupling means of toy trains functions automatically after the fashion of the couplings of full sized trains to couple adjacent cars when one is backed into another, the uncoupling of adjacent toy train cars using one's fingers, presents difficulties. This is especially true with the popular smaller sizes of toy trains and finger uncoupling usually results in multiple car derailment. Thus, track section-carried uncouplers have come into extensive use. These, while effective admit of car-uncoupling only at specific points in the track system.

Therefore the present invention has for its primary object to overcome the aforesaid objections by providing a simple, inexpensive, easily operated and highly efficient portable hand-operated uncoupling tool which can be employed for car uncoupling at any point in the track system and without car derailment.

The invention further contemplates a device as characterized which is available for uncoupling different types of couplings and when operated with at least certain types of couplings cooperates with the ends of rail-supporting ties to prevent over-manipulation of the coupler-actuating elements of adjacent cars.

Invention also resides in certain novel features of construction, combination and arrangement of the various parts, and in modes of operation thereof, as will be apparent to toy train enthusiasts and others versed in the art.

In accordance with the patent statute requirements, I have illustrated in the accompanying drawings a now preferred example of the invention. However, it is to be understood that my inventive concept is susceptible of other mechanical expressions within the spirit and scope of the subject matter claimed hereinafter.

In the drawings, wherein the same reference characters have been used to designate the same parts wherever they appear in the several views—

Fig. 1 is a perspective view of a familiar toy car coupling, fragments of adjacent cars, and part of a curved track being also illustrated;

Fig. 2 is another perspective showing disconnected the opposed coupling elements of Fig. 1 and also a familiar type of track section-carried uncoupler;

Fig. 3 is a side elevation of my improved portable hand operated uncoupler in use;

Fig. 4 is a section on the line 4—4 of Fig. 3;

Fig. 5 is a top view of the uncoupler of Figs. 3 and 4;

Fig. 6 is a section on the line 6—6 of Fig. 4; but showing portions of the coupling members broken away;

Fig. 7 is an elevation looking toward the inner surface of one of the duplicate arm sections of my uncoupler;

Fig. 8 is a side elevation looking toward the right side thereof as seen in Fig. 7;

Fig. 9 is a back view of the Fig. 8 element;

Fig. 10 is a top plan view thereof; and

Fig. 11 is a fragmentary elevational view showing a modification.

Referring to the drawings by reference characters, Fig. 1 shows a conventional coupling for adjacent cars 7 of a toy train which runs on the rails 8 that are supported by ties 9. Since the interengageable car-provided elements of the coupling are identical except that one is a "right" and the other a "left," so to speak, a description of one will suffice for both.

Thus, the conventional coupling disclosed comprises the two horizontally swingable and axially alignable draw bars 10, each of which has at its outer end the integral, elongated and coplanar rearwardly inclined cam-form coupling head 11 whose rear end provides the draft hook portion 11a. As will be understood from Figs. 1 and 2, when the draft bars 10 swing inwardly, these draft hooks 11a interengage to provide the coupling. The inner end of each draft bar 10 extends through the open forward end of a car truck-carried casing 12 and has a bearing hole 13 (Fig. 2) through which a vertical casing-carried pivot pin (not shown) extends.

It should also be explained that the draw bar-supporting casings 12 have the usual spring means (not shown) tending to swing the draw bars 10 inwardly; and also a conventional stop means (not shown) to limit said inward swinging beyond the point when draft hooks 11a engage as in Fig. 1.

Rearwardly spaced from each coupling head 11 the under surface of each draw bar 10 has a depending integral lug 14 which fixedly carries the depending laterally offset pin 15. As will be understood from Fig. 1, pins 15 are located on opposite sides of the longitudinal axis of the substantially aligned and coupled draw bars 10, 10; and also that the respective pins 15 lie outwardly of the plane of the free rear end of the related head-provided coupling hook portion 11a.

Prior art uncouplers

Since, as mentioned earlier herein, it is very difficult and often impossible to uncouple the cars with the fingers without car derailment, various track section-carried uncouplers have been provided for the illustrated and other toy train couplings. However, these are objectional as they facilitate uncoupling only at specific points in the track layout.

An example of a track-provided uncoupler is shown in Fig. 2 wherein stiff, arched and inwardly bowed wires 16a, 16b which are secured at their ends to opposite end-adjacent sides of the track-supported base 16. When a car connecting coupling located between the closely spaced intermediate portions of wires 16a, 16b, pins 15 are actuated into alignment longitudinally of the draw bars 10 to disengage the head-provided draft hooks 11a, as indicated in Fig. 2. This means that the leftmost coupling unit 10, 15, as viewed in Fig. 2, is actuated outwardly in the direction of arrow 17 by wire 16a; and that wire 16b actuates the rightmost unit 10, 15 outwardly in the direction of arrow 17a.

The manually operated uncoupler of the present invention

Referring now to my manually operable tong-like uncoupler 18, it is seen to comprise the duplicate arm or jaw sections 19 having the inturned lower end portions 21 which carry the straight terminal portions 23 which parallel the plane of arms 19 and are reinforced by backing ribs 24. Arm terminals 23, during the uncoupling operation, are adapted to support the upright tool 18 on the surface which supports the track 8, 9 (see Fig. 4).

Extending inwardly from the curved lower arm end portions 21 are the opposed broad, flat and alignable coupling pin actuators 25. Above the intermediate portions of arms 19 they are angled inwardly as at 22 to

provide the straight portions 26 which terminate in the upper head ends 20.

Each upper arm head end 20 provides at one side an arcuately curved bearing portion 27 and at the opposite side a bearing recess 28. The bearing portion 27 of one arm fits into the bearing recess 28 of the companion arm 19 as shown. The bearing portions 27 are connected by a pin 30 which extends through concentrically located bearing holes 30a in said bearing portions.

As shown in Figs. 5, 7, 9 and 10, the bearing portions 27 provide opposed shoulders 29 which are spaced as shown in Fig. 5 when the arms, or jaws, are in the Fig. 4 position but which engage, as indicated in dotted lines in Fig. 4, to limit outward movement under the influence of a presently to be referred to spring 34.

Below the interfitting recess and bearing portions 28, 27 the arms are thickened as indicated at 31, and provide the opposed shoulders 32. The opposed faces of the thickened arm portions 32 have the opposed and communicating seat portions 33 for the substantially V-form leaf spring 34 which tends to spread the arms apart. The outer surfaces of the thickened arm portions 31 have the finger-receiving surface recesses or seats 35 for the thumb 36 and forefinger 37 of the operator.

Operation summarized

When the adjacent cars 7 of Fig. 1 are to be uncoupled, the operator grasps the tool between thumb and forefinger as indicated in dotted lines in Fig. 4. Finger seats 35 enable him to readily control the inward movement of the normally separated jaws 19 and also to engage the jaw terminals 23 on the track supporting surface opposed the coupling to be uncoupled.

The lower jaw terminals 23 elevate the actuators 25 to just the right height to engage the coupling member-operating pins 15 and actuate them inwardly to substantial coupling axis alignment as indicated in Figs. 4 and 6. Such inward pin (15) movement actuates the inwardly spring tensioned coupling elements 10, 15 and 10, 15 outwardly to disengage the load-sustaining hooks 11a, 11a of the coupling heads. Engagement of the opposed jaw terminals 23 with the outer ends of intervening ties 9 prevents such additional inward movement of jaws 19 as might bring about car derailment. When the coupling hooks 11a, 11a have been disengaged and the cars are pulled apart, the depending pins 15 slide freely over the ends of 25, 25.

Obviously the device is adapted for various types of

toy train couplings having depending actuators for coupling release means. This applies whether the said actuator pins 15 move in horizontal or vertical planes. But when such actuator pins 15 move in a vertical plane to effect coupling release, the opposed ends of actuators 25 will be frictionally cushioned by rubber, or otherwise, as at 25a in Fig. 11.

Having thus described my invention, what I claim is:

1. A portable manually operable uncoupler for the car couplings of toy railroad trains and the like, comprising connected inwardly shiftable members having opposed coupling release element-engaging portions, and a member carried by said shiftable members and engaging the train track or equivalent supporting surface to dispose the release element-engaging means in position thereabove to operatively engage said coupling release elements.
2. The structure of claim 1, and said inwardly shiftable members comprising pivotally connected jaws.
3. The structure of claim 1, and said inwardly shiftable members comprising pivotally connected jaws, and spring means normally urging said jaws outwardly.
4. The structure of claim 1, and said inwardly shiftable members comprising pivotally connected jaws, spring means normally urging said jaws outwardly, and means carried by said jaws and limiting outward movement of the same under the action of said spring means.
5. The structure of claim 1, combined with tie-supported rails resting upon said supporting surface and wherein the opposite ends of a rail-supporting tie engage said supporting surface-engaging members to terminate inward movement of the same at approximately the time that the coupling release elements are engaged thereby, whereby to prevent over inward actuation of said release element engaging portions.
6. The structure of claim 1, and said inwardly shiftable members comprising pivotally connected jaws, and the exterior pivot-adjacent surfaces of said jaws having finger-receiving recesses.
7. The structure of claim 1, and said inwardly shiftable members comprising pivotally connected jaws, the opposed pivot-adjacent jaw surfaces having opposed recesses, and spring means removably seated in said jaw recesses for normally actuating the jaws outwardly.
8. The structure of claim 1, and the opposed ends of said release element-engaging portions being faced with a compressible friction material.
